WARREN F. FRASER, OF WESTBORO, MASSACHUSETTS

GRINDING MACHINE

Application filed July 25, 1927. Serial No. 208,185.

This invention relates to grinding machines and is especially concerned with grinding machines of the automatic type.

It is the general object of the invention to improve machines of this character with a view to producing more accurate and uniform results, and facilitating the making of exact and rapid adjustments.

The invention will be herein disclosed as embodied in a machine of the type in which the wheel head and the work support are mounted to produce relative approaching and receding movements of the work and grinding wheel. In such machines the approaching movement must be controlled very exactly in order to produce accurate results. I have found that in machines of this type the presence of oil films between the parts which limit the approaching movement is decidedly detrimental to the high degree of accuracy required in many classes of work. Accordingly, it is an important object of this invention to devise a construction in which errors arising from this cause will be eliminated.

The nature of the invention will be readily understood from the following description when read in connection with the accompanying drawings, and the novel features will be particularly pointed out in the appended claims.

In the drawings,

Figure 1 is a plan view showing those parts of a grinding machine with which the present invention is more especially concerned;

Fig. 2 is a perspective view showing a detail of construction;

Fig. 3 is a plan view of a portion of the machine frame and bed, the wheel head being removed;

Fig. 4 is a vertical, cross-sectional view approximately on the line 4—4, Fig. 1;

Fig. 5 is a cross-sectional view through the wheel head and a part of the supporting bed therefor, the section being taken approximately on the line 5—5, Fig. 1; and

Fig. 6 is a front view, partly in vertical cross-section, showing certain details of the wheel head adjusting mechanism.

The machine shown comprises a grinding wheel 2 and a work support 3 which is shown somewhat diagrammatically in Fig. 4. This machine is of the so-called cylindrical type and it is designed especially for grinding work having cylindrical or tapered external surfaces such as pistons, shafts, shackle bolts, and the like. A work support of any suitable construction may be used in it, the support shown at 3 being designed to revolve an article of work W around a stationary axis while the grinding wheel 2 operates on it, suitable mechanism being provided, if desired, to produce a relative traversing motion of the wheel and work.

The work support is mounted on upright extensions of the machine frame or base 4, while the wheel 2 is mounted in a wheel head or wheel support 5 which can be moved toward or from the work. For this purpose the support 5 is mounted on a bed 6 which is provided with a V-shaped guideway 7 and a flat guideway 8, (see Figs. 3 and 5) the support 5 having correspondingly shaped parts to fit these guideways. This construction permits a sliding movement of the whole wheel head or wheel support 5 toward or from the work W.

The approaching movement of the wheel toward the work is produced by a spring 10, Fig. 3, which is held in a casing 12 and which serves to force a plunger 13 outwardly, this plunger carrying a threaded stud or bolt 14 which is adjustable in the plunger 13. The stud or bolt 14 acts on one end of a lever 15, the opposite end of this lever bearing against a bar 16, Fig. 4, which is rigidly mounted in the wheel support 5 but is adjustable relatively thereto. So far as the operation of the spring 10 on the wheel support is concerned, the bar 16 may be considered to be an integral part of the support 5. It will be evident from an inspection of Figs. 3 and 4 that the spring 10 tends constantly to force the wheel 2 toward the work W.

The receding movement of the wheel relatively to the work is produced by a power driven mechanism which comprises a cam 17, Fig. 4, secured fast on a driven shaft 18 and arranged to oscillate a lever 20 which is ful-

crummed on the machine frame at 21. An inclined guideway is provided on the upper side of this lever in which a wedge 22 is mounted, this wedge having a rod 23 connected to it which extends through an upright projection 24 on the rearward end of the lever. Nuts 25—25, Fig. 4, threaded on the right-hand end portion of the rod 23 serve to adjust this rod longitudinally, and this adjustment, in turn, adjusts the wedge 22 in its guideway. Bearing on the wedge 22 is an upright pin or rod 26, and one arm 27 of a bell crank lever bears on the upper end of this pin, while its other arm 28 engages a vertical face 30 formed on the bar 16. The bell crank lever 27—28 is supported on a pivot 31 which is mounted in ears 32—32, Fig. 2, of a bracket 33 which is set into a socket formed in the machine bed 6, the bracket being bolted securely to the bed so that it is to all intents and purposes, so far as operation is concerned, an integral part of the bed.

It will be observed that when the machine is in operation the spring 10 will tend to hold the wheel 2 in contact with the work W, but that when the high part of the cam 17 operates to raise the lever 20, this movement will be transmitted through the pin 26 and bell crank lever 27—28 to the bar 16 which, being rigid with the wheel support 5, will give the wheel a receding or withdrawing movement away from the work. In a completely automatic machine the work is changed during this receding movement and a new article of work is presented to the wheel before the cam 17 again permits the lowering of the lever 20 and allows the spring 10 to move the wheel 2 again into contact with the work. The shape of this cam is such that after the wheel has engaged the work the cam still controls the rate of approach or feed of the wheel.

As above indicated, an important feature of this invention resides in the mechanism which limits the work approaching movement of the wheel 2. Referring to Figs. 2, 3 and 4 it will be seen that a bar 34 is secured in the recess 35 in the bracket 33, and that when the lowering movement of the lever 20 occurs, the work approaching movement of the wheel will be limited by the engagement of portions of the upright face 30 on the bar 16 with faces 39 of this fixed bar 34. In other words, this bar 34 acts as a stop, since it is mounted in a fixed position with reference to the machine frame. The time at which the approaching movement of the wheel head or work support 5 is stopped in the rotation of the cam 17 may be varied by adjusting the wedge 22 in the manner above described. That is, the bar 16 will strike the stop 34 and thus limit the approaching movement of the wheel head at some time during the stroke which is imparted to the lever 20 by the cam 17, and the point in this stroke at which such

stopping of the movement of the wheel head occurs may be determined by adjusting the wedge 22. The portion of the stroke of said lever 20 which occurs after the wheel head is stopped results simply in a dwell or pause in the movement of the wheel head. It will be noted that the right-hand face, Fig. 4, of the lever arm 28 moves into and out of contact with the upright face 30 on the bar 16, and that the upright face 30 also moves into and out of contact with the faces 39 on the bar 34. The pivot or fulcrum 31 for the lever 27—28 is positioned in a pocket formed in the base 6 which is adapted to hold a quantity of oil so that the pivot may be well lubricated, but the cooperating faces of the stop 34 and bar 16 are all located a substantial distance above this pocket so that they are kept substantially free of oil. They are also protected from dust by the fact that they are located under the wheel head 5 in a substantially closed chamber. This arrangement thus eliminates inaccuracies in the work which otherwise would be caused by the presence of oil or dust films on the surfaces of the parts which limit the work approaching movement.

In order to adjust the wheel angularly with reference to the work, the bed 6 on which the wheel support 5 slides is mounted on a horizontal planed surface on the frame or base 4 and is pivoted on a bushing 36 through which the pin 26 projects. An extension 37 of this bed projects forward through the front of the frame 4 and overlies a bracket 38 rigid with the frame. Adjusting screws 40—40 are threaded through upright lugs formed on this bracket and bear against the opposite sides of the extension 37 where they can be conveniently manipulated to adjust the angular relationship of the grinding wheel and the work. A bolt 41 projects through both the extension 37 and the bracket 38 and serves to lock the bed in its adjusted position.

For the purpose of adjusting the grinding wheel to work of different diameters, the bar 16 is mounted to slide in the wheel support 5 but is prevented from rotating by the key 42, Fig. 4, and the forward or left-hand end of the bar is screw threaded, as shown at 43. An internally threaded sleeve 44 is mounted on the threaded portion 43 of the bar and is secured by means of a key and a nut 47 to a hand wheel 45 through which the sleeve may be rotated to adjust the bar 16, and consequently the wheel 2, toward or from the work. The sleeve is held by parts 46 and 47 against axial movement relatively to the bracket 56 which is secured to the support 5 by means of the part 59. This permits a fine adjustment of the bar 16 with relation to the wheel head, and the periphery of the hand wheel 45 preferably is graduated, as shown in Fig. 1, to cooperate with a sta-

tionary pointer 48, Figs. 1 and 4, in making these adjustments.

For extremely fine adjustments a micrometer screw mechanism also is provided. 5 That is, a worm wheel 50 is bolted securely to the hand wheel 45 which is keyed to the sleeve 46 so that it must rotate with it, and a micrometer screw 51, Fig. 6, is arranged to mesh with and drive the worm wheel 50. 10 This screw is mounted on the lower end of a shaft 52 which is rotatably supported in a bracket 53, the upper end of the shaft being provided with a graduated finger wheel 54. The bracket 53 is pivoted at 55, Fig. 6, on 15 a stationary casing 56 in which the screw threaded sleeve 44 is mounted, and this pivotal support permits the movement of the micrometer screw 55 into or out of mesh with the worm wheel 50. Normally the screw is 20 held out of contact with the worm wheel by a spring 57, Figs. 1 and 6, which encircles a rod 58 and bears against a portion of the bracket 53. It may be moved into mesh with the worm wheel, however, by a cam 60 having 25 a handle 61, the cam being mounted to rotate on the rod 58 and cooperating with a stationary cam member 62, secured on said rod, to force the lower end of the bracket inwardly far enough to carry the screw 51 30 into mesh with the worm wheel 50 and hold it there. A pin 63, Fig. 6, projecting from the cam 60 and, working in a slot formed in the bracket 53, limits the operative movement of the cam. Fig. 6 shows the micrometer adjusting mechanism in its operative position. 35 When the handle 61 is moved backwardly the spring 57 immediately throws the screw 51 out of mesh with the worm wheel 50.

The screw threaded mechanism which 40 operates with the left-hand end, Fig. 4, of the bar 16 serves to make adjustments of the wheel head or wheel support 5 relatively to the bar 16, the bar being held between the levers 15 and 28, so that the grinding wheel 45 is adjusted relatively to the work, and these 45 adjustments can be made very minute, if desired, through the use of the micrometer mechanism. These adjustments also determine the relationship of the grinding 50 wheel to the work.

The invention thus provides a grinding machine in which extreme accuracy can be obtained and in which this accuracy is not likely to be disturbed by the presence of oil 55 films, dust or the like.

While a preferred embodiment of the invention has been herein shown and described, it will be understood that the invention may be embodied in other forms without departing 60 from the spirit or scope thereof.

Having thus described my invention, what I desire to claim as new is:

I claim:

1. In an automatic grinding machine, the 65 combination of a wheel support, a work sup-

port, a machine bed having guideways upon which one of said supports is mounted for sliding movement to produce a relative approaching or receding movement of the work and grinding wheel, a bar adjustable in said 70 slide support, screw threaded means for making fine adjustments of said bar relatively to said slide support, power driven mechanism operable through said bar to produce said receding movement; a spring for 75 producing said approaching movement, said mechanism including a power driven cam and a lever mechanism through which motion is transmitted from said cam to said bar, one of the levers of said mechanism including 80 an arm arranged to act on the bar in one direction; and a stop for engaging said bar and limiting its movement in the opposite direction.

2. In an automatic grinding machine, the combination of a grinding wheel support, a work support, a machine bed having guideways upon which one of said supports is mounted for sliding movement to permit relative approaching and receding movements 85 of the work and grinding wheel, a machine frame supporting said bed, a hollow pivot connecting said bed and frame for angular adjustment of the bed on the frame, a bar 90 adjustable in said slide support, power driven mechanism operable through said bar to produce said receding movement, and yieldable means for producing said approaching movement, said mechanism comprising a cam and connections between said 95 cam and said bar, including a member slidably mounted in said hollow pivot, for moving said bar in one direction.

3. In an automatic grinding machine, the combination of a grinding wheel support, a work support, a machine bed having guideways upon which one of said supports is mounted for horizontal sliding movement to produce relative approaching and receding movements of the work and grinding wheel, a horizontal bar adjustable in said slide support, screw threaded means for adjusting said bar relatively to said slide support, said bar having an upright shoulder, a bell crank lever mounted on said bed and having an arm to engage said shoulder and a second arm extending at an angle thereto, a power driven cam, a lever arranged to be actuated by said cam, and connections between the latter lever and the second arm of said bell crank lever for operating said bell crank lever to cause it to engage said bar and thereby produce said receding movement of said slide support.

4. In an automatic grinding machine, the combination of a grinding wheel support, a work support, a machine bed having guideways upon which one of said supports is mounted for horizontal sliding movement to produce relative approaching and receding 125 movement of the work and grinding wheel, a horizontal bar adjustable in said slide support, screw threaded means for adjusting said bar relatively to said slide support, said bar having an upright shoulder, a bell crank lever mounted on said bed and having an arm to engage said shoulder and a second arm extending at an angle thereto, a power driven cam, a lever arranged to be actuated by said cam, and connections between the latter lever and the second arm of said bell crank lever for operating said bell crank lever to cause it to engage said bar and thereby produce said receding movement of said slide support.

130

- movements of the work and grinding wheel, a horizontal bar adjustable in said slidable support, screw threaded means for adjusting said bar relatively to said slidable support, said bar having an upright shoulder, a bell crank lever mounted on said bed and having an arm to engage said shoulder and a second arm extending at an angle thereto, a power driven cam, a lever arranged to be actuated by said cam, connections between the latter lever and the second arm of said bell crank lever for operating said bell crank lever to cause it to engage said bar and thereby produce said receding movement of said slidable support, a spring for producing said relative approaching movement, and a stop rigid with the machine frame and arranged to engage said bar to limit said relative approaching movement.
- 5 20 5. In an automatic grinding machine, the combination of a grinding wheel support; a work support; a machine bed having guideways upon which one of said supports is mounted for sliding movement to produce relative approaching and receding movements of the work and grinding wheel; a rod adjustable in said slidable support; screw threaded means for adjusting said rod relatively to said support; power driven mechanism operable through said rod to control said approaching movement; and a stop rigid with the machine frame for engaging said rod and limiting said approaching movement, said mechanism comprising a power driven cam, a lever operated thereby, means for transmitting the motion of said lever to said rod, and means adjustable to vary the range of movement imparted to said slidable support by said cam.
